UNITED STATES PATENT OFFICE.

CHARLES B. MOORE, OF EVANSTON, ILLINOIS.

FRONT ARCH FOR NARROW LOCOMOTIVE-FURNACES.

No. 904,211.

Specification of Letters Patent.

Patented Nov. 17, 1908.

Application filed May 20, 1907. Serial No. 374,722

To all whom it may concern:

Be it known that I, CHARLES B. MOORE, a citizen of the United States, and a resident of Evanston, Cook county, Illinois, have invented certain new and useful Improvements in Front Arches for Narrow Locomotive-Furnaces, of which the following is a full, clear, and exact description, such as will enable others skilled in the art to which it appertains to make and use the same.

My invention relates to improvements in locomotive boiler furnaces and has special reference to improvements in the construction and arrangements of the front arches in such furnaces.

More particularly, this invention is a modification of that which is shown and described by me in a companion application of even date herewith, Serial No. 374,721, in which I have disclosed a locomotive boiler furnace having the usual arch tubes and equipped with a refractory front arch comprising a central or body portion composed of several rows of bricks resting upon the arch tubes and abutting the flue sheet, and edge or marginal bricks of greater width than the spaces between the body portion and the side sheets, filling said spaces.

The object of this invention is to provide a front arch for locomotive boiler furnaces having the general characteristics of the one above mentioned, but which will be of such modified construction as to be particularly adapted to furnaces of the narrow fire box type. Furnaces of this type require an arch of different construction than those used in wide furnaces. This is due to two reasons, namely: the irregularity of the side sheets of the furnace, which requires an arch of varying width; and the impracticability of taking the air in through the front of the furnace, as to drop the front end of the arch low enough for this purpose would place it too near the grate, which necessitates taking the air in through the sides of the furnace.

The particular object of this invention is to improve the form and construction of the front arches for narrow locomotive boiler furnaces that bricks of definite shapes and sizes shall be adapted for use in all boilers of this type.

A further object is to provide a front arch for narrow locomotive boiler furnaces formed of bricks of definite size and shape,

which shall so snugly fit the walls of the furnace as to prevent the vibration of the arch as a whole, or of its individual bricks.

A still further object of this invention is to provide a front arch for narrow locomotive boiler furnaces of such improved construction that parts thereof may be readily removed to afford access to the stay bolts, which are in front of or above the arch, for the purpose of inspection and repair.

Further objects of the invention appear hereinafter.

My invention consists, generally, in a locomotive boiler furnace having the usual arch tubes, in combination with a refractory arch, comprising a bottom end brick abutting the flue sheet and of substantially the width of the furnace, a central row of bricks of substantially the same width as the group of arch tubes and resting thereon, and side or marginal bricks filling the spaces between the edges of the central bricks and the curved side sheets.

My invention further consists in a locomotive boiler furnace having the usual arch tubes, in combination with a refractory arch comprising a bottom end brick of substantially the width of the furnace and abutting the end of the flue sheet, a body portion formed of other bricks and of substantially the width of the group of arch tubes and resting thereon, side bricks of greater width than the spaces between the body portion of the arch and the side sheets, and closing said spaces; longitudinal air ducts in said body portion bricks and a transverse air duct in the lowermost brick of said body portion, said transverse air duct communicating with the outer air through the sides of the furnace.

Further, my invention consists in a locomotive boiler furnace having the usual arch tubes and provided with air intake tubes in its sides, in combination with a front arch comprising a bottom end brick abutting the flue sheet and reaching substantially across the furnace, a single longitudinal row of bricks of substantially the same width as the group of arch tubes and having holes which register to form longitudinal air ducts, the lower brick of said row having a transverse air duct communicating with the longitudinal ducts, two small bricks fitted between the ends of said lower brick and the side sheets.

and having air ducts which connect the duct in the lower central brick with said intake tubes, and marginal bricks of greater width than the spaces between the central row of 5 bricks and the side sheets and resting thereon.

Further, my invention consists in a locomotive boiler furnace containing arch tubes, in combination with an arch comprising a 10 central longitudinal row of bricks resting upon the arch tubes, and side bricks supported upon the edges of said central row of bricks and leaning against the side sheets, the arch tubes being arranged beneath the 15 joints between said central row of bricks and the side bricks. And further, my invention consists in various novel details of construction and in combinations of parts, all as hereinafter described and particularly 20 pointed out in the claims.

My invention will be more readily understood by reference to the accompanying drawings, forming a part of this specification and in which;

25 Figure 1 is a longitudinal vertical section of a locomotive boiler furnace of a narrow fire box type, equipped with a front arch embodying my invention; Fig. 2 is a horizontal section on substantially the line 2—2 of Fig. 1, the lower right hand corner of 30 the arch being broken away to disclose the air ducts; Fig. 3 is a cross section on the line 3—3 of Fig. 1; Fig. 4 is a cross section on the line 4—4 of Fig. 1; and Fig. 5 is a 35 similar section on the line 5—5 of Fig. 1.

Referring to the drawings, A indicates the flue sheet, B the side sheets, and C the rear sheet of a locomotive boiler furnace of which D is the crown sheet and E the arch tubes. 40 The arch tubes extend longitudinally through the furnace and support the refractory arch, F.

The arch F is arranged slantingly within the furnace, and preferably comprises a 45 front or base portion containing cinder holes and of practically the width of the furnace; a central or body portion of less width than the furnace and formed of a number of bricks resting upon the base portion; and, 50 side or marginal bricks closing the spaces between said body portion and the side sheets. The front or base portion is indicated in the drawings at f. This is preferably a single brick of substantially the width of the fire 55 box and is provided with legs or extensions, f', which abut or rest against the flue sheet, A, forming cinder discharge openings. As the brick f touches the flue sheet only at the two points where the legs, f', rest against it, 60 uniformity of flue sheet temperature is insured. The body portion of the arch comprises a bottom brick, f²; intermediate bricks, f³, and, a top or deflector brick, f⁴. The brick f² is provided with a transverse 65 air duct, f⁵, extending from end to end

thereof, and two short ducts, f⁶, connecting said transverse duct with ducts f⁷ formed in the bricks f³, and which extend longitudinally through the arch to the top or deflecting brick, f⁴.

G indicates the air intakes, which are tubes extending through the sides of the furnace, opposite the ends of the transverse duct, f⁵. As before stated, in boiler furnaces of the type under consideration, it is impracticable 70 to drop the front end of the arch low enough to have the air intake through the front of the furnace, hence the necessity of admitting the air through the sides thereof. Between the ends of the bottom brick, f², and the side 75 sheets of the furnace are small bricks, f⁸, having air ducts, f⁹, connecting the duct f⁵ with the air intakes, G. The ends of the brick f² are upwardly and inwardly inclined, forming wedge shaped spaces 80 between them and the flue sheet, B, and the bricks f⁸ are correspondingly formed, to fit the wedge shaped spaces. As furnaces of substantially the same size or type are seldom 85 the same width between the side sheets, 90 and, as the bricks f² are of uniform size, the spaces between the ends of said bricks and the side sheets will vary in different furnaces. However, the wedge shaped bricks, f⁸, will always fit snugly in place and hold 95 the central portion of the arch with sufficient firmness to prevent vibration. Although the bricks f⁸ will fit in place, no matter what the space may be, the ends of the ducts f⁹ therein will not always exactly register with the 100 duct f⁵ and the intakes G. Accordingly the ends of the duct f⁵ and the outer ends of the ducts f⁹ are flared, in order to form an unobstructed passage for the air, whatever the vertical positions of the bricks f⁸ may be.

The intermediate bricks, f³, and the rear deflector bricks, f⁴, are of the same shape in cross section as the brick f²; hence the body portion of the arch is of uniform cross section throughout, and has upwardly and inwardly inclined edges, F', throughout its length. To close the space between the edges of the body portion of the arch and the flue sheets, I provide the side or marginal bricks, w, which are supported by the 110 edges of the body portion of the arch and rest against the side sheets, B. These bricks are of irregular shape, as the space they are 115 designed to fill is irregular, the arch being positioned aslant between the flaring side 120 sheets. Hence I form these bricks of substantially the size and shape of the spaces they are designed to fill, and provide them with projections, w', to rest against the side sheet. These projections may be easily 125 chipped off to fit the bricks in place. The inner edges of the bricks, w, are doubly beveled, as indicated at w², making the two bricks, w and w', interchangeable. The bricks w, w', may be readily fitted to fur- 130

naces varying widely in size, and the projections, w' , admit of easy adjustment by chipping them if need be.

It will be noted that the bulk of the weight of the bricks, w , will rest upon the edges of the body bricks, f^2 and f^4 , and to best support them, I arrange the arch tubes, E , substantially beneath the joints between them. If preferred, non-fusible material may be placed between the several bricks, in order that the arch or a portion thereof may be readily removed, without breaking any of its parts. To get at the stay bolts, the side or marginal bricks may be readily lifted out of place without disturbing the remainder of the arch, exposing said bolts for inspection or repair. This construction forms an arch which, though formed of bricks of a definite size and shape, may be fitted to furnaces of various widths, and which, when placed in position, will fit the fire box so snugly as to prevent vibration of its component members or of the arch as a whole. Further, the arch may be readily dismantled to get at the flue sheet or the stay bolts for inspection or repair.

As various modifications of my invention will readily suggest themselves to one skilled in the art, I do not limit my invention to the specific constructions described herein.

Having thus described my invention I claim as new and desire to secure by Letters Patent:

1. A locomotive boiler furnace having irregular upwardly and outwardly flared side walls and provided with longitudinally arranged inclined arch tubes, in combination with a refractory front arch resting upon said tubes and comprising a bottom front brick abutting the front wall or flue sheet of the furnace, a body portion composed of a longitudinal row of similar bricks, of uniform cross-section throughout, and irregular side bricks adapted to close the spaces between said body portion and said side walls, substantially as described.

2. A locomotive boiler furnace having irregular upwardly and outwardly flared side walls and provided with longitudinally arranged inclined arch tubes, in combination with a refractory front arch resting upon said arch tubes, and comprising a bottom front brick abutting the front wall or flue sheet of the furnace, a body portion formed of a longitudinal row of similar bricks of less width than the narrowest part of the furnace, and of uniform cross-section throughout, and irregular side bricks closing the spaces between said body portion and said side walls, substantially as described.

3. A locomotive boiler furnace having irregular upwardly and outwardly flared side walls and provided with longitudinally arranged inclined arch tubes, in combination

with a refractory front arch resting upon said arch tubes and comprising a body portion formed of a longitudinal row of similar bricks of uniform cross-section throughout, and irregular side bricks conformed to said side walls and adapted to close the spaces between said body portion and said side walls, said side bricks having lugs or points upon their outer edges to rest against the side walls of the furnace, substantially as described.

4. A locomotive boiler furnace having a group of longitudinal, inclined arch tubes, in combination with a refractory arch, comprising a bottom front brick of substantially the width of the furnace and abutting the front wall or flue sheet of the furnace, a body portion formed of a row of similar bricks longitudinally arranged and substantially the width of the group of arch tubes and resting thereon, side bricks of greater width than the spaces between the body portion of the arch and the side walls, and adapted to close said spaces, longitudinal air ducts through said body portion, and a transverse air duct in the lowermost brick of said body portion, said transverse air duct being in communication with the outer air through the sides of the furnace, substantially as described.

5. A locomotive boiler furnace having irregular side walls and provided with a group of longitudinal, inclined arch tubes, in combination with a refractory arch, comprising a bottom end brick of substantially the width of the furnace and abutting the flue sheet, a body portion rising from said end brick and formed of a longitudinal row of similar bricks of substantially the width of the group of arch tubes, and resting thereon, irregular side bricks of greater size than the spaces between the body portion of the arch and the side walls, and closing said spaces, longitudinal air ducts through said body portion and a transverse air duct in the lowermost brick of said body portion, said transverse air duct communicating with the air through the sides of the furnace, substantially as described.

6. A locomotive boiler furnace having irregular upwardly and outwardly flared side walls, and provided with longitudinally arranged inclined arch tubes, in combination with a refractory arch resting upon said arch tubes, and comprising a body portion formed of a longitudinal row of similar bricks, of substantially the width of the arch tubes and resting thereon, said body portion having upwardly and inwardly inclined edges, side bricks correspondingly beveled to fit the edges of said body portion and resting thereon, said side bricks being of greater width than the spaces between the sides of said body portion and the sides of the furnace and having outer edges conformed to

said side walls, and adapted to close said spaces, substantially as described.

7. A locomotive boiler furnace having irregular upwardly and outwardly flared side walls, and provided with longitudinally arranged arch tubes, in combination with a refractory front arch, said arch comprising a body portion of less width than the narrowest portion of said furnace, and having upwardly and inwardly inclined edges, and irregular side bricks supported upon the edges of said body portion and leaning against the side sheets, said arch tubes being arranged beneath the joints between said body portion and said bricks, substantially as described.

8. A locomotive boiler furnace provided with longitudinally arranged inclined arch tubes, in combination with a refractory front arch resting upon said tubes, and comprising a central or body portion of less width than said furnace, and having upwardly and inwardly inclined edges, and side bricks of greater size than the spaces between the edges of said body portion and the sides of the furnace, and adapted to close said spaces, said side bricks having doubly beveled edges to rest against and be supported by the inclined edges of said body portion, and lugs upon the outer edges to rest against the side sheets, substantially as described.

9. A locomotive boiler furnace having longitudinally arranged inclined arch tubes, and provided with side air intake tubes, in combination with a front arch comprising a bottom end brick abutting the flue sheet of substantially the width of the furnace, a single longitudinal row of bricks of substantially the same width as the group of arch tubes, and having holes therein which register to form longitudinal ducts through the arch, the lower brick of said row also having a transverse air duct, wedge-shaped bricks fitted between the ends of said lower brick and the side sheets, and having air ducts therethrough connecting said transverse air duct with said air intake tubes, and side bricks of greater width than the spaces be-

tween the central row of bricks and the side sheets, and supported thereby to substantially fill said spaces, substantially as described.

10. A locomotive boiler furnace of the narrow fire box type, containing inclined arch tubes, in combination with a single brick resting upon said tubes and against the flue sheet, channeled bricks forming the body of an arch and supported by said single brick and said tubes, channeled lateral wedge bricks abutting the lower arch-body-forming bricks and communicating with the channels therein, air tubes in the sides of the furnace communicating with said wedge bricks and other wedge bricks preventing lateral movement of the body-forming-bricks on said tubes, substantially as described.

11. A locomotive boiler furnace of the narrow fire box type, having inclined arch tubes and provided with air tubes in its sides in combination with a refractory arch body resting upon said tubes and containing one or more longitudinal air channels and channeled wedge bricks extending between the arch body and the air tubes in the furnace sides, the channels in said wedge bricks communicating with the longitudinal channels in said body, substantially as described.

12. A locomotive boiler furnace containing a group of longitudinally arranged arch tubes in combination with a refractory arch body arranged on said arch tubes and containing air ducts and wedge shaped bricks arranged between the sides of the furnace and the arch body and having channels of ducts communicating with the ducts in the arch body and tubes in the side walls of the furnace communicating with the ducts in said wedge bricks, substantially as described.

In testimony whereof, I have hereunto set my hand, this 3d day of May, 1907, in the presence of two subscribing witnesses.

CHARLES B. MOORE.
